UNITED STATES PATENT OFFICE.

LLOYD T. HUNTER, OF REVERE, MASSACHUSETTS.

FIRE-ESCAPE.

1,191,790.

Specification of Letters Patent. Patented July 18, 1916.

Application filed April 23, 1915. Serial No. 23,403.

To all whom it may concern:

Be it known that I, LLOYD T. HUNTER, a citizen of the United States, residing at Revere, in the county of Suffolk and State 5 of Massachusetts, have invented certain new and useful Improvements in Fire-Escapes; and I do hereby declare the following to be a full, clear, and exact description of the invention, such as will enable others skilled 10 in the art to which it appertains to make and use the same.

The invention relates to fire escapes.

The object of the present invention is to improve the construction of fire escapes and 15 to provide a simple, practical, and reliable fire escape of strong and durable construction, adapted to be cheaply manufactured and capable of lowering persons to the ground with absolute safety.

20 A further object of the invention is to provide a fire escape of this character equipped with automatic controlling means adapted to cause persons of different weights to descend expeditiously at the same rate of 25 speed and capable of gradually reducing the speed as the person nears the ground.

It is also the object of the invention to 30 provide double acting controlling means of the escapement type adapted to cause a step by step rotary movement of a shaft in either 35 direction when the same is subjected to the weight of a person whereby two lines reversely wound around the shaft may be employed so that when one person is descending 40 with one line the other line will be winding around the shaft so as to be in condition for the use of the next person as soon as the one using it reaches the ground, whereby the fire escape will be capable of continuous operation without loss of time.

With these and other objects in view the invention consists in the construction and novel combination and arrangement of parts hereinafter fully described, illustrated in the 45 accompanying drawings and pointed out in the claims hereto appended, it being understood that various changes in the form, proportion and minor details of construction may be resorted to without departing from 50 the spirit or sacrificing any of the advantages of the invention.

In the drawing Figure 1 is a front elevation of a fire escape constructed in accordance with this invention, the casing for the 55 escapement control being in section, Fig. 2 is a vertical sectional view on the line 2—2

of Fig. 1, Fig. 3 is a horizontal sectional view on the line 3—3 of Fig. 2.

Like numerals of reference designate corresponding parts in the several figures of the 60 drawing.

In the accompanying drawing in which is illustrated the preferred embodiment of the invention, the frame of the escape comprises side bars 1, spaced vertically disposed supporting bars 2 located at opposite sides of the center of the frame, and top and bottom horizontal connecting bars 3, and 4.

The side bars 1 and the central supporting bars 2 have their terminals 5 and 6 bent at 70 right angles and bolted or otherwise secured to the connecting bars 3 but the frame may be constructed in any other desired manner to form the substantially oblong spaced frame sections, as will be readily understood. The side bars and the central supporting bars are provided with alined bearings 7 and 8 for the reception of a transverse shaft 9 to which is keyed or otherwise secured an escapement wheel 10 located between the central vertical supporting bars 2 and provided with outwardly tapered teeth 11 having rounded ends 12 adapted to be engaged by dogs or tappets 13 of an escapement lever 14. The escapement lever 85 14 which is mounted on a transverse pivot 15 has a forked lower portion, the sides or arms of which are approximately L-shaped and constitute the said dogs or tappets. The upper portion of the lever constitutes a gravity 90 acting oscillatory arm 16 which is tapered downwardly. The forked portion of the lever straddles the upper portion of the escapement wheel and the teeth of the latter successively engage and alternately contact 95 with the end of one of the dogs or tappets and the inner face of the other dog or tappet which breaks or checks the movement of the escapement wheel and thereby controls the rotation of the horizontal shaft 9 causing a 100 step by step partial rotary movement of the same. The teeth of the escapement wheel are tapered and rounded at their outer ends and the depending engaging portions of the dogs or tappets are of a width substantially equal to the length of the teeth and of a length substantially equal to the 105 distance between the teeth so that one tooth of the wheel fits in the angle of the engaged dog or tappet and is arranged at an acute 110 angle to the inner edge of the same. The rotary movement of the shaft is varied by

- varying the weight of the upwardly extending gravity acting oscillatory arm 16 and when the shaft 9 is subjected to the strain of the weight of a person, the step by step rotary movement of the shaft will be constant irrespective of the weight of the person so that heavy and light persons will be lowered to the ground at the same rate of speed. The escapement mechanism is located within a suitable casing 17 constructed of suitable material preferably sheet metal and secured between the inner vertical supporting bars 2. The top 18 of the casing is preferably curved or arcuate and the upper edge or face 15 of the oscillatory gravity acting arm 16 is correspondingly shaped so as to clear the casing in its backward and forward movement to opposite sides of the perpendicular center of the device.
- 20 The shaft is equipped with reversely wound lines 19 of flat belting or webbing but any other desired construction of lines may of course be employed in connection with the gravity escapement. The lines 19 by being relatively wide and flat will roll up or wind up on the shaft and it is unnecessary to employ cheek pieces or a drum construction but the same may be used if desired. When one of the lines is unwinding the other is being wound around the shaft, so that when a person reaches the ground the other line will be wound up and ready for use. By this arrangement the fire escape is capable of continuous operation as 25 no time is lost in rearranging the device for use after it has descended to the ground. Also as the gravity acting escapement positively controls the rotary movement of the

shaft, the speed of a person descending will gradually decrease as he approaches the ground owing to the decrease in the diameter of the roll of the line of belting as a less amount of belting will be unwound from the roll, the length of line unwound from the roll decreasing with the decreasing diameter of the roll. This will enable a person to land lightly upon the ground without jar or injury.

What is claimed is:—

A fire escape of the class described including a frame comprising spaced vertically disposed oblong frame sections and top and bottom connecting bars maintaining the frame sections in spaced relation, each frame section being composed of inner and outer side bars having their terminals bent at an angle and secured to the top and bottom connecting bars and a relatively narrow vertical casing located at the space between the frame sections and secured to the inner side bars of the latter and extending outwardly therefrom at right angles to the said frame, a horizontal shaft journaled in and extending entirely across the frame at the lower portion of the casing, lines reversely wound around the horizontal shaft at opposite sides of the casing within the frame sections and escapement mechanism mounted within the said casing and connected with the shaft for controlling the rotation thereof.

In testimony whereof I affix my signature in presence of two witnesses.

LLOYD T. HUNTER.
